ATTORNEY

UNITED STATES PATENT OFFICE.

BENJAMIN F. DE KLYN, OF NEW YORK, N. Y.

DESIGN FOR A TABLET.

SPECIFICATION forming part of Design No. 32,311, dated March 6, 1900.

Application filed October 11, 1899. Serial No. 733,321. Term of patent 7 years.

To all whom it may concern:

Be it known that I, BENJAMIN F. DE KLYN, a citizen of the United States, residing in the city, county, and State of New York, have invented a new and original Design for a Tablet; and I do hereby declare that the following is a full, clear, and exact description of the same.

Reference is to be had to the accompanying drawings, forming part of this specification, in which—

Figure 1 is a plan view of a tablet embodying my new design; and Fig. 2 is a cross-sectional view of the same on the line 2 2, Fig. 1.

As shown in the drawings, the leading and material feature of my design consists of an

upper convex surface and a lower flat surface, the two surfaces meeting at an edge, which is scalloped around its entire periphery and beveled at the indentations *a* of the scalloped edge. A section of the upper surface is substantially an arc of a circle.

Having thus described my invention, what I claim as new, and desire to obtain by Letters Patent, is—

The design for a tablet substantially as herein shown and described.

In testimony whereof I have hereunto set my hand this 21st day of September, 1899.

BENJAMIN F. DE KLYN.

In presence of—

FRANK DE K. HUYLER,
LOUIS M. FULTON.
